UNITED STATES PATENT OFFICE.

ROBERT O. KING, OF NORTH TONAWANDA, NEW YORK.

CONSTRUCTION OF HORTICULTURAL BUILDINGS.

1,170,911.

Specification of Letters Patent.

Patented Feb. 8, 1916.

Application filed October 9, 1913. Serial No. 794,212.

To all whom it may concern:

Be it known that I, ROBERT O. KING, a subject of the King of England, residing in North Tonawanda, county of Niagara, State of New York, have invented a certain new and useful Improvement in Construction of Horticultural Buildings, of which the following is a specification.

This invention relates to buildings having glazed roofs and with or without glazed side walls, and comprises a new construction at the juncture of the roof and side wall, including the eaves, and also means for receiving and discharging from the buildings water of condensation on the under side of the roof.

The main supporting frame is herein shown as consisting of tubular posts and tubular rafters connected by elbows, each elbow being provided with an upwardly angularly arranged bracket to which is attached the eave and which with the upper side of the elbow supports a gutter adapted to catch water of condensation from the underside of the roof.

The eave is composed of a strip of rolled metal longitudinally bent, secured to the brackets of the elbows, and arranged at substantially the same angle as the roof and supporting it. The other side extends downward and is attached to the side wall or facia strip at the top thereof. The lower edge of the vertical side of the eave is bent or flared outwardly in such manner as to cause water running over the eave to fall away from the side wall or side sashes of the structure.

In the accompanying drawing, Figure 1 is a vertical view showing the essential features of the invention, with some of the parts in section; Fig. 2, a plan view of the same, and Fig. 3, a perspective view of one of the connecting pieces or brackets that joins the roof sash bars to the metal eave.

The frame of the building comprises a series of vertical tubular posts *a*; elbow castings *b* screwed on the tops of the posts; tubular rafters *c* held in the other ends of the elbows, which are split and clamped on the rafters by bolts *d*; and the eave *e* secured by screw-bolts *f* to an inclined flange of a bracket *g* extending from, and preferably integral with, each of the elbows *b*. The eave *e* is formed from a strip of metal, longitudinally bent to form an upper section *h* which is secured to the brackets *g*

and lies in substantially the plane of the roof. The lower section of the eave plate is vertically disposed and its lower edge *j* is curved outwardly. The eave plate constitutes the longitudinal connection between the frames *a*, *b*, *c*, which are suitably spaced. Brace rods *k* may be used, having their ends bent and passed through side sockets on the elbows *b* and held therein by nuts *t*.

Angular brackets *m* are provided for connecting the lower or eave ends of the roof sash bars *n* to the eave *e*; the lower inner limbs of the brackets being secured to the roof sash bars by screws *o*. The means provided for securing the brackets to the eave plate consists of lugs *p* and *q* extending laterally from the upper limbs *r* of the brackets and between which the upper edge of the eave plate seats. The uppermost lugs *p* are tapped to receive set screws *s*, which by acting on the top side of the eave plate firmly clamp the brackets on the edge thereof. This arrangement affords means for readily placing and holding the sash bars in desired spaced positions. The glass plates *z* are held in grooves in the sash bars *n*, and their lower edges extend over the upper side of the eave, and between them and the eave are glazing strips *u*, of suitable metal, bent upwardly around the lower edge of the glass and downwardly against the upper edge of the eave. Seated in curved recesses formed in the elbows *b* and along the upper sides of the elbow brackets *g* is a gutter *v* that receives water of condensation. To the inner side of the vertical part *i* of the eave plate is secured the upper bar of a side sash frame *w* carrying glass *x*. Such side sash frames are provided with hinges *y*.

By the construction and arrangement of the various parts here described green-house buildings may be made simple, strong and effective. There will be little obstruction to light at the eave and the structure will be weather-tight. The greater part of the inner face of the eave is exposed to the internal heat of the house and receives also, by conduction, heat from the brackets *g* and *m* thus preventing accumulation of snow and ice at the eave. The flared formation of the lower edge of the eave delivers drip water away from the side wall.

I claim:

1. In a building of the character described, a sheet metal eave longitudinally

bent with one flange angularly arranged in substantially the plane of the roof and the other flange substantially vertical, and the lower edge of said vertical flange outwardly flared, roof sashes secured to the upper flange, side sashes secured to the inner side of the vertical flange, and interior frame supports to which the eave is directly connected by its angularly arranged flange.

2. In a building of the character described, a sheet metal eave longitudinally bent with one flange angularly arranged and substantially in the plane of the roof and the other flange substantially vertical, and the lower edge of said vertical flange outwardly flared, roof sashes secured to the upper flange, side sashes secured to the inner side of the vertical flange, and interior frame supports to which the eave is directly connected by its angularly arranged flange, glazing strips extending around the lower edges of the glass of the roof sashes, between the glass and the eave and around the upper edge of the eave, through the medium of which the glass is upheld by the eave.

3. In a building of the character described, a sheet metal eave longitudinally bent with one flange angularly arranged and

substantially in the plane of the roof and the other flange substantially vertical, and the lower edge of said vertical flange outwardly flared, roof sashes secured to the upper flange, side sashes provided at their upper ends with hinges, said hinges being secured to the inner side of the vertical flange, and interior frame supports to which the eave is directly connected by its angularly arranged flange.

4. In a building of the character described, a sheet metal eave longitudinally bent with one flange angularly arranged and substantially in the plane of the roof and the other flange substantially vertical, roof sash bars, angular brackets each fastened by one of its limbs to a sash bar, and having on the other limb two lugs adapted to receive between them the upper edge of the eave and set-screws passing through one of the lugs and adapted to clamp the eave firmly against the other lug.

In testimony whereof, I have hereunto subscribed my name.

ROBERT O. KING.
